[57] CLAIM

The ornamental design for a paint brush support, as shown and described.

DESCRIPTION

FIG. 1 is an environmental perspective view of a paint brush support showing my new design;

FIG. 2 is a top view thereof;

FIG. 3 is a right side elevational view with the left side elevational view being a mirror image thereof;

FIG. 4 is a front elevational view with the rear elevational view being a mirror image thereof; and,

FIG. 5 is a bottom view thereof.

The broken line showing of a bucket and paint brush in FIG. 1 is for demonstrative purposes only and forms no part of the claimed design.
